UNITED STATES PATENT OFFICE.

ROBERT G. HALL, OF PORTLAND, OREGON.

TRENCH-PICK.

1,323,630.

Specification of Letters Patent.

Patented Dec. 2, 1919.

Application filed July 22, 1918. Serial No. 246,081.

To all whom it may concern:

Be it known that I, ROBERT G. HALL, a citizen of the United States, residing in the city of Portland, county of Multnomah, and 5 State of Oregon, have invented certain new and useful Improvements in Trench-Picks, of which the following is a specification.

My invention relates to trench picks, and more particularly to a pick adapted to be 10 thrust into the ground by the weight of the person using the same, as is a hand spade, instead of being struck into the ground by a swinging movement, as are the usual hand picks now in use.

15 There are many advantages in such a pick, the principal ones of which are the elimination of the sound of the blow struck by the usual hand pick, my improved hand pick being noiseless in use, thus making it possible 20 to use the same in close proximity to the enemy without alarming him. My improved pick can also be used with great efficiency with the user in a crouching position, and without the necessity of swinging the 25 pick above the head in order to get a forceful blow, as is required with the usual pick. It also has the advantage of use in close quarters with greater ease and efficiency, as in tunnels and dug-outs. It is also possible 30 to work faster with the foot pick, for there is less lost motion and the entire weight of the body can be quickly put on to the pick and its manipulation is under full control 35 of the hands and foot of the user. My pick also makes a very effective weapon, where necessary, being used much as is a bayonet in close fighting.

In order to fully illustrate and describe my improved trench pick, I have shown one 40 practical form thereof on the accompanying drawings which I will now describe.

Figure 1 is a side elevation thereof; and Fig. 2 is an edge view thereof.

45 My improved pick comprises a pick point or spike 1, a handle 2, and a foot rest 3. The handle is joined to the spike 1 by an offset portion 2^a, whereby to make possible the positioning of the foot rest 3 directly over the pick spike 1, thus giving a direct 50 longitudinal thrust to the spike 1 when the weight of the body is placed upon the foot rest 3. The handle 2, in this preferred form

of the invention, it will be seen, is in direct alinement with the pick spike 1, thus any weight applied to the handle is also transmitted in direct lines to force the pick spike into the ground. Under the foot rest 3 is a corner piece or plate 4, made sharp on its edge, whereby it will operate to cut roots, or other obstructions, as the pick is forced into 60 the earth. The lower end of the handle, below the foot rest, is also formed into a similar cutting edge, as at 5. These bracket-like portions or corners 4 and 5, also form a broad bearing to prevent the upper end of 65 the pick spike from cutting into the ground when the pick handle is forced downwardly toward the earth in a prying movement, after the spike has been thrust into the earth. The pick can be turned so as to use 70 the right foot, or the left foot on the foot rest, as may be most convenient to the user. Should the pick be used as a weapon, in emergency, the foot rest serves as a guard 75 for the hand which grasps the pick adjacent thereto.

I am aware that slight changes can be made in my foot or trench pick, as here shown for purposes of illustration, and I do not, therefore, limit the invention to the 80 form shown, except as I may be limited by the hereto appended claim.

I claim:

An article of the character referred to comprising in combination a handle turned 85 outwardly and downwardly at its lower end in offset form, a spike secured at its upper end to the side of the offset portion of said handle, in longitudinal alinement with the handle proper, a foot rest extended across 90 the top of said spike with its attached end anchored in the offset portion of said handle, and a corner piece under said foot rest in the angle between said foot rest and the upper end of said spike, said corner piece 95 being sharpened on its outer edge, substantially as shown and described.

Signed at Eugene, Lane county, Oregon, this 13th day of July, 1918.

ROBERT G. HALL.

In presence of—

J. M. DEVERS,
BERNICE E. CAGLEY.
